Geo. P. Kimmel. ATTORNEY

UNITED STATES PATENT OFFICE.

VICTOR H. COHN, OF NEW YORK, N. Y.

DESIGN FOR A RING.

59,195.

Specification for Design.

Patented Oct. 4, 1921.

Application filed March 5, 1921. Serial No. 450,107. Term of patent 7 years.

To all whom it may concern:

Be it known that I, VICTOR H. COHN, a citizen of the United States, residing at New York, in the county of New York and State of New York, have invented a new, original, and ornamental Design for a Ring, of which the following is a specification, reference being had to the accompanying drawing, forming a part thereof.

Figure 1 is a side elevation of a ring, showing my new design.

Fig. 2 is an edge elevation of a ring, showing my new design.

What I claim is:

The ornamental design for a ring, as shown.

VICTOR H. COHN.
